H. MESINGER

SADDLE

Filed June 11, 1925

Inventor

Henry Mesinger

By his Attorney

C. P. Gabel

UNITED STATES PATENT OFFICE.

HENRY MESINGER, OF NEW YORK, N. Y.

SADDLE.

Application filed June 11, 1925. Serial No. 36,323.

To all whom it may concern:

Be it known that I, HENRY MESINGER, a citizen of the United States, and resident of New York, in the county and State of New York, have invented certain new and useful Improvements in Saddles, of which the following is a specification.

This invention relates to saddles, and more particularly to an improved cushioning means for saddles such as are used upon bicycles, motorcycles and similar vehicles.

It is the primary object and purpose of my present improvements to provide an improved form, construction and mounting of the rear cushioning springs for the saddle top whereby shocks and jars which would otherwise be transmitted to the saddle through the vehicle frame are effectively absorbed or cushioned.

20 In one practical embodiment of the invention, I provide the saddle with a longitudinally extending main spring having spaced portions adapted to be suitably clamped upon the vehicle frame. These

25 spaced portions of the spring at their rear ends are bent to provide vertically disposed guides for the parallel end portions of a spring supporting hanger rod which is pivotally mounted upon the under side of the rear end of the saddle top. Preferably, each cushioning spring is formed from a single length of resilient wire having an upper conically coiled compression section and a lower cylindrically coiled compression

35 section. The ends of the main spring extend downwardly through the latter portions of the cushioning springs and terminate in guide eyes closely surrounding the hanger rods and upon which the lower ends of the

40 cushioning springs bear. Thus, in the rebound or upward movement of the saddle, the rear ends of the main spring will coact with the lower ends of the cushioning springs and compress the same to thereby absorb the rebound shock.

It is another object of the invention to provide means for attaching the cushioning system to the saddle top in which the use of nuts or other fastening elements which may

50 easily work loose and be lost is avoided while at the same time, upon occasion, the saddle top may readily be detached and removed from the elements of the cushioning system.

55 With the above and other objects in view, the invention consists in the improved

mounting or cushioning means for vehicle saddles and in the form, construction, and relative arrangement of its several parts as will be hereinafter more fully described, illustrated in the accompanying drawing and subsequently incorporated in the subjoined claims.

In the drawings, wherein I have illustrated a simple and practical embodiment of the invention, and in which similar reference characters designate corresponding parts throughout the several views,—

Figure 1 is a vertical sectional view taken on the line 1—1 of Fig. 2;

Fig. 2 is a fragmentary bottom plan view, and

Fig. 3 is a detail perspective view of one of the fastening elements for securing the saddle top to the cushioning means.

In the drawings, for purposes of illustration, I have shown a saddle top of conventional form. This saddle top may be of any approved construction, but as herein shown consists of a base plate 5 having marginal flanges 6, said plate being covered on its lower side by a suitably shaped leather layer 7. The saddle also includes a top layer 8 of leather between which and the base plate 5 suitable padding material 9 is arranged. The two leather layers 7 and 8 are brought together at their edges and stitched or otherwise permanently secured to each other as at 10.

The cushioning means for the saddle top includes a main longitudinally extending spring 11 which is formed of resilient steel wire of relatively heavy gauge and is bent to provide longitudinally extending spaced portions adapted to be securely connected with a part of the vehicle frame by means of a suitable clamping device such as that indicated at 12. At their forward ends the longitudinally spaced portions of this spring are upwardly curved and connected by a transverse intermediate portion 13 of the spring which is pivotally mounted in a clip 14 secured to the under side of the saddle top. As herein shown, this clip consists of a sheet metal plate bent to provide a central bearing sleeve for the part 13 of the spring. Each end of this plate is provided with a longitudinally extending slot as shown at 15 and these slots are adapted to be arranged in registering relation with a similar slot 16 provided in the base plate 5 of the saddle top and the slot 17 in the leather layer 7. Before

the upper leather layer 8 is secured in place, a fastening member 18 shown in detail in Fig. 3 is applied. As herein illustrated this member consists of a shank provided at one end with laterally diverging lugs 19 and at its other end with a suitable head 20. The distance between the ends of the lugs 19 is such that said lugs may be readily passed through the coinciding slots 15, 16 and 17. The fastening member is then turned through an angle of 90° to position said lugs 19 transversely of said slots. As shown in Fig. 1 of the drawings, the lower end portion of the metal clip 14 is then bent downwardly against one side of the lugs 19 and serves to lock said fastening member against rotation whereby said lugs might become positioned in alignment with the slots 15, and thus release the clip 14 from its connection in the saddle top.

To the rear end of the saddle top, the intermediate portion of a U-shaped hanger rod 21 is connected by clips 22 which are similar to the clips 14 and are also secured to the under side of the saddle top by fastening members 23 of the same construction as the member 18 just described.

Each of the depending end portions of the hanger rod 21 supports a cushioning spring. Each of these springs is formed from a length of resilient steel wire of somewhat lighter gauge than the spring 11 and has an upper conically or spirally coiled section 24, the coils gradually decreasing in diameter from the lower to the upper end of said section and the upper end coil closely surrounding the hanger rod. Each spring also includes a lower cylindrically coiled section 25, the upper end coil of which is connected with the lower end coil of the section 24 by the obliquely extending portion 26 of the spring wire. The lower end coil of the spring section 25 terminates in an eye 27 which closely surrounds the hanger rod 21 but permits of free movement of said rod through the eye.

Rearwardly of the clamping device 12, the spaced portions of the main spring 11 are bent to provide guide loops 28 for the end portions of the rod 21, said loops being of considerably less diameter than the lower sections 25 of the cushioning springs. From these loops 28, the ends of the main spring 11 are extended downwardly as shown at 29 through the respective spring sections 25 and terminate at their lower ends in the guide eyes 30 for the hanger rod, said guide eyes 30 providing bearings for the lower ends 27 of the spring sections 25. Upward movement of the hanger rod through the eyes 30 is limited by the washer plates 31 which are retained upon the ends of the hanger rods by the transverse pins or keys 32 or other suitable retaining means.

In the operation of the device above de-

scribed, when the wheels of the vehicle encounter an obstruction, in the downward movement of the saddle top at its rear end under the weight of the rider, as the vertical end portions of the hanger rod 21 move downwardly through the guide loop 28 and eye 30 on the ends of the main spring 11, the initial movement is cushioned by the spring sections 25. Further downward movement of the saddle top is cushioned by the spring sections 24. This compression of the spring sections 24 is transmitted through the spring sections 25 to the lower ends of the spaced parts of the main spring 11, the resistance of which is finally overcome so that said rear end portions of the main spring will cushion any further or excessive movement of the saddle top. In the rebound or upward movement of the saddle top, the spring sections 24 and 25 expand, and the guide eyes 30 on the lower end of the spaced parts of the main spring 11 exert an upward bearing pressure against the lower end coil of the spring sections 25, thus tending to compress said spring sections and thereby effectively absorb the rebound shock. I have herein shown the parts 29 and 30 as integral extensions of the main spring 11, but it will be apparent that if desired, these parts may be separately formed and the rear ends of the spring 11 formed with eyes to receive the vertical parts of the rod 21 and exerting an upward bearing pressure against eyes formed on the upper end of the parts 29. The same result is thereby produced, namely, that the main spring 11 tends to yieldingly urge the parts 29 upwardly and thereby compress the coils of the spring sections 25.

From the foregoing description considered in connection with the accompanying drawing, the construction and manner of operation of my present improvements will be clearly understood. It will be seen that by reason of the new form of the vertical cushioning springs and the cooperative arrangement of these springs in connection with the rear ends of the main spring 11 that a very effective shock absorbing means is provided and the transmission of such shocks or jars through the vehicle frame to the rider is reduced to a minimum. It will also be observed that while I provide means for very securely fastening the saddle top to the elements of the cushioning means, no nuts or other parts are used which might readily work loose and be lost. At the same time, when necessary it is possible to readily detach the saddle top by simply bending the down turned ends of the clips 14 and 22 upwardly so that the fastening members 18 and 23 can be rotated, and thus permit the terminal lugs of these fastening members to pass through the slots in the ends of the clips. While I preferably pro-

vide fastening members of the form shown with comparatively heavy lugs 19, if desired split rivets may be used as a substitute for such fastening members.

5 It is also to be understood that the particular form in which the main spring 11 is illustrated in the accompanying drawing is not essential, and this spring may be of various other desired shapes and also 10 mounted in position upon the seat post or other frame part of the vehicle in any desired manner. Therefore, while I have herein shown one satisfactory embodiment of my present improvements, it is nevertheless to be understood that the essential features thereof might be incorporated in various other alternative structures, and I therefore, reserve the privilege of resorting to all such legitimate changes as may be 15 fairly embodied within the spirit and scope 20 of the invention as claimed.

I claim:

1. In combination with a saddle top, 25 cushioning means for said saddle top including a longitudinally extending main spring pivotally connected at its forward end with the saddle top and having spaced portions provided with guides at their rear ends, a vertically disposed hanger pivotally 30 connected to the rear end of the saddle top and having spaced parts movable through said guides, and a cushioning spring on each 35 of said spaced parts of the hanger, and said guides on the spaced parts of said main spring constituting bearings for the lower ends of said cushioning springs.

2. In combination with a saddle top, 40 cushioning means for said saddle top including a longitudinally extending main spring pivotally connected at its forward end with the saddle top and having spaced portions provided with guides at their rear ends, a vertically disposed hanger pivotally 45 connected to the rear end of the saddle top and having spaced parts movable through said guides, and a cushioning spring on each of said spaced parts of the hanger, each of said cushioning springs having an upper conically coiled section, 50 and a lower cylindrically coiled section, the terminal coils of the latter sections of said spring having bearing pressure upon the extremities of the spaced parts of said main spring.

55 3. In combination with a saddle top, a main longitudinally extending spring pivotally connected at its forward end with the saddle top and having spaced portions, a hanger pivotally connected with the saddle 60 top at its rear end and having spaced vertically disposed depending parts, a cushioning spring surrounding each of said hanger parts, each of said springs having an upper conically coiled section and a lower cylindri- 65 cally coiled section, the rear ends of said

spaced parts of the main spring extending downwardly through said cylindrically coiled sections of the respective cushioning springs and terminating in guide eyes for the hanger and also constituting bearings 70 for the lower ends of the cushioning springs.

4. In combination with a saddle top, a main longitudinally extending spring pivotally connected at its forward end with said saddle top, said spring having spaced parts each of which is bent at its rear end to provide vertically spaced guides, a hanger pivotally connected to the rear end of the saddle top and having spaced parts extending 75 through said guides, and a cushioning spring surrounding each of the hanger parts and bearing at its upper end against the hanger and at its lower end upon one of the guides of said main spring. 80

5. In combination with a saddle top, a U-shaped hanger rod pivotally connected with said saddle top at its rear end and having spaced depending parts, and a cushioning spring surrounding each of said hanger parts, each of said springs having an upper conically coiled section and a lower cylindrically coiled section connected with the lower end coil of the conical section by a sharply angled part of the spring 95 wire vertically spacing said coiled sections from each other. 90

6. In combination with a saddle top, a U-shaped hanger rod pivotally connected with said saddle top at its rear end and having spaced depending parts, and a cushioning spring surrounding each of said hanger parts, each of said springs having an upper conically coiled section and a lower cylindrically coiled section connected with the lower end coil of the conical section by an 100 obliquely extending part of the spring wire, and a longitudinally extending supporting spring pivotally connected at its forward end to the saddle top and having spaced parts extending at their rear ends between the upper and lower sections of the cushioning springs and provided with means constituting guides for the hanger parts, and 105 connections between said guide means and the bottom coil of the lower cylindrical section of the cushioning spring tending to compress the latter and cushion the return movement of the saddle top to its normal 110 position. 115

7. In combination with a saddle top and cushioning means therefor, said saddle top having a base plate provided with slots therein, means for fastening parts of the cushioning means to the under side of the saddle top consisting of metal clips each bent to provide a sleeve therein and having a longitudinal slot in each of its end portions adapted to register with one of the 125 slots in the saddle plate, and a fastening 130

- member having lugs at one end adapted to be inserted through the slot in the saddle plate and the slots in the ends of said clips and then turned to position the lugs at right angles to the latter slots, and one end of said clip adapted to be bent at an angle in respect to the other end thereof and against one side of said lugs to lock the fastening member against turning movement.
8. In combination with a saddle top, a member extending longitudinally beneath the saddle top adapted to be fixed upon a cycle frame and pivotally connected at its forward end to the saddle top, the rear end of said member being vertically extended and provided with vertically spaced guides, a depending rod pivotally connected with the rear end of the saddle top and loosely engaged in the guides for movement therethrough, and a cushioning spring surrounding said rod and bearing at its lower end upon the lowermost guide.
9. In combination with a saddle top, cushioning means for said saddle top including a spring member extending longitudinally beneath the saddle top and pivotally connected therewith at its forward end, the rear end of said spring member being angularly disposed and formed with spaced guides, a rod pivotally connected with the rear end of the saddle top and loosely extending through said spaced guides, and a cushioning spring surrounding said rod and bearing at its lower end against one of said guides.
10. In combination with a saddle top, a bearing below and in spaced relation to the saddle top, and a cushioning member interposed between said bearing and the saddle top and having integrally connected portions successively and independently responsive to cushion the downward movement of the saddle top.
11. In combination with a saddle top, a bearing below and in spaced relation to the saddle top, and a cushioning member interposed between said bearing and the saddle
- top and having independently compressible portions successively responsive to cushion the downward movement of the saddle top.
12. In combination with a saddle top supported for vertical movement, cushioning means for said saddle top including parts successively and independently compressible in the downward movement of the saddle top, and additional cushioning means for the saddle top responsive to the cumulative forces of compression borne by said first named cushioning means.
13. In combination with a saddle top supported for vertical movement, a cushioning member arranged beneath the saddle top and having integrally connected portions successively and independently compressible in the downward movement of the saddle top, and additional cushioning means for the saddle top responsive to the cumulative forces of compression borne by said cushioning member.
14. In combination with a saddle top mounted for vertical movement, a cushioning member arranged beneath the saddle top and having independently compressible portions successively responsive to the downward movement of the saddle top, and an additional cushioning member constituting a bearing for the lower end of said first named member and responsive to the cumulative forces of compression borne by said first named member.
15. In combination with a vertically movable load receiving member, a coiled cushioning spring for said member having upper and lower sections independently responsive to relatively different load pressures and integrally connected by an intermediate, sharply angled part of the spring vertically spacing said sections from each other.

In testimony that I claim the foregoing as my invention, I have signed my name hereto.

HENRY MESINGER.
